UNITED STATES PATENT OFFICE.

JOSEPH C. POTTS, OF BERWYN, ASSIGNOR TO HIMSELF AND JOSEPH H. COATES, OF PHILADELPHIA, PENNSYLVANIA.

ART OF WEAVING IMITATION SEERSUCKER FABRIC.

SPECIFICATION forming part of Letters Patent No. 284,145, dated August 28, 1883.

Application filed April 2, 1883. (No model.)

To all whom it may concern:

Be it known that I, JOSEPH C. POTTS, a citizen of the United States, residing in Berwyn, Chester county, Pennsylvania, have invented 5 an Improvement in the Art of Weaving Imitation Seersucker Fabrics, of which the following is a specification.

The object of my invention is to make a cheap-imitation of the well-known "seersucker" fabric, which is studded on one side with 10 projections, due to corresponding pits on the opposite side, these being caused by the different contractile properties of the silk and cotton threads of which the fabric is composed. The imitation fabric is made entirely 15 of cotton or linen threads, in the manner which I will proceed to explain, reference being had to the accompanying drawings, in which—

20 Figure 1 is a perspective diagram, illustrating the two sets of warp-threads which I use; and Fig. 2 an exaggerated plan of the warp-threads and part of the reed.

It should be stated that no new mechanism, 25 is required to carry my invention into effect, as the fabric can be woven in any ordinary loom. It is not even essential that two warp-beams should be used. For these reasons it has been deemed best to restrict the illustrations to diagrams, as the best means of conveying to those skilled in weaving operations 30 the true character of my invention.

The warp consists of alternate sets of two or more threads each, these sets being represented by the alternate black and white stripes *a* and *b* in Fig. 1, the threads themselves being too thin to be shown without creating confusion.

It is essential, in weaving the fabric, that 40 one set of warp-threads should be under greater tension than the other, and this may be brought about by using two warp-beams, A and B, one for the set of warp-threads *b* and the other for the other set of warp-threads, different degrees of tension being imparted to the two sets of threads by usual let-off appliances used in connection with warp-beams in ordinary looms. We will suppose,

in the present instance, that the black stripes represent the slack threads and the white 50 stripes the tight threads of the warp.

It is also essential, in carrying out my invention, that there should be more or less friction of the dents of the reed against the slack warp-threads, while the tight warp-threads 55 are free between the dents. This may be brought about in two ways: First, the dents of the reed may be uniform throughout, as usual, and the sets of threads indicated by the black lines in Fig. 2 may be so thick 60 that there will be considerable friction of the dents against them, while the tight warp-threads (indicated by the lighter lines in Fig. 2) are free between the dents. Another plan is to make all the warp-threads, both slack 65 and tight sets, of uniform thickness, and to so arrange the dents of the reed that the distance between the dents for the slack threads shall be less than the distance between the dents for the sets of tight threads. This 70 plan, however, while it results in the desired friction of the dents on the slack threads, is more expensive than the first plan, as it involves the necessity of making a special reed.

If the requirements above described are adhered to and the weaving be proceeded with in the usual manner, the sets of threads will be fed forward to the shedding devices under different degrees of tension, and the sets of 80 threads having the least amount of tension will be drawn or moved forward by the friction of the reed thereon in beating up the weft, the result being the production of a fabric in which plain stripes alternate with 85 shirred or puckered stripes.

Although I have shown two warp-beams, one warp-beam only may be used, providing that one set of threads is wound more tightly upon it than the other set.

I claim as my invention—

The improvement herein described in the art of weaving fabrics, which consists in arranging the threads of the warp in alternate sets of two or more threads each, feeding 95 said sets of warp-threads forward to the shed-

ding devices under different degrees of tension, and moving or drawing forward the sets of threads having the least amount of tension by the friction of the reed thereon, in
5 beating up the weft, whereby a fabric is produced having alternate plain and shirred stripes, as set forth.

In testimony whereof I have signed my name to this specification in the presence of two subscribing witnesses.

JOSEPH C. POTTS.
